DESIGN FOR A REFRIGERATOR CABINET

Edward L. Hayes, Detroit, Mich., assignor to
Gratiot Fixture & Supply Co., Detroit, Mich.,
a corporation of Michigan

Application April 18, 1938, Serial No. 76,585

Term of patent 7 years

To all whom it may concern:

Be it known that I, Edward L. Hayes, a citizen of the United States of America and residing at Detroit, in the county of Wayne and State of Michigan, have invented a new, original, and ornamental Design for a Refrigerator Cabinet, of which the following is a specification, reference being made to the accompanying drawing, forming part thereof.

The figure is a perspective view of a refrigerator cabinet showing my new design, the doors being shown in dotted lines.

The dominant features of the design reside in the rounded corner members and the panel at the front center of the cabinet, as shown.

The appearance of the side of the refrigerator cabinet not seen in the drawing is similar to the side which is shown.

I claim:

The ornamental design for a refrigerator cabinet, substantially as shown and described.

EDWARD L. HAYES.
